UNITED STATES PATENT OFFICE.

ERNEST C. TAYLOR, OF ELYRIA, OHIO.

FURNACE.

Application filed August 26, 1920, Serial No. 406,111. Renewed October 5, 1923.

To all whom it may concern:

Be it known that I, ERNEST C. TAYLOR, a citizen of the United States, and a resident of Elyria, in the county of Lorain and State of Ohio, have invented certain new and useful Improvements in Furnaces; and I do hereby declare the following to be a full, clear, and exact description of the invention, such as will enable others skilled in the art to which it appertains to make and use the same.

My invention relates to dampers and damper operating mechanisms, and to furnace radiators.

15 It has previously been proposed to provide furnace radiators having detouring paths extending from the combustion chamber to the chimney flue, and in such constructions the cleaning-out door on the front part of the radiator usually lines up with the fire door and the ash door, but due to the positioning of the furnace relative to obstructing walls such as the wall of a coal bin and other obstructions, it 20 sometimes becomes necessary to so swing the radiator around that the cleaning-out door will not line up with the front of the furnace.

It has been found desirable that the control of the damper should still be retained at a point in the front of the furnace, just as though the front of the radiator were arranged to coincide with the front of the furnace. In order to accomplish this, I 30 control the damper in the short cut or direct flue, through the medium of a gear mounted on the shaft of the damper, which shaft is vertically disposed, so that the gear lies in a horizontal plane on top of the radiator.

At a point coincident with the vertical axis of the radiator, which axis is the central axis on which the radiator rotates, when its front is shifted out of alignment with the front of the furnace, I mount a second gear wheel. This centrally located gear wheel meshes with the first gear mentioned. With this arrangement, I can retain the control of the damper in the front of the furnace, regardless of the position of the radiator, and as far as I am aware, I am the first one to obtain this result, and I am the first one to provide the means

above indicated for accomplishing this purpose.

Therefore, among the objects of my invention, are the following:—

To provide a pivoted member centrally located with reference to the furnace, whereby the damper and the direct flue may 60 be controlled from a given point, with respect to the foundation of the furnace, and regardless of the rotation of the cap or radiator of the furnace.

To provide details of improvements tending to increase the efficiency and serviceability of a heating furnace.

To accomplish the foregoing and other useful ends, my invention contains the means hereinafter more fully set forth and 70 claimed.

Referring to the accompanying drawing, which is a top plan view, of the radiator ring for a furnace, the said ring comprising a plurality of flues, A, B, and C, a 75 clean-out opening K and an outlet opening L, the three flues shown comprising the straight flue C and the branching flues A and B meeting at a common point in the rear of the radiator adjacent the chimney, 80 the flue C leading directly to the combustion chamber and adapted to most directly convey the exhaust smoke and gases from the combustion chamber to the chimney, the other two flues A and B together 85 being arc shaped and each forming a branching path, substantially similar in vertical section, from the fire box, about the circumference of the radiator to the chimney.

In the direct flue C, I provide a damper D pivotally supported on a shaft d, for variably limiting the flow of exhaust gases through the flue C.

Carried on the shaft d, I mount a gear 95 E. The flue C is connected to the combustion chamber located below T by a conduit M leading to the fire box, the conduit M and the damper D being shown in the drawing by dotted lines as these are located below 100 the upper surface of the radiator ring flues.

Coincident with the central vertical axis of the furnace and the radiator, I have mounted a second gear F, which is pivoted on the outside of the shell of the radiator, 105 and of a diameter to suitably mesh with the

gear E. It will be seen that by rotating the gear F, I can control the damper D. The mechanism for controlling the gear F consists of an arm f, which is provided with a hole whereby the arm f may be pivoted at one end of the shaft G to the gear F, which shaft G is coincident with the centrally vertical axis of the furnace. On this arm f, I provide a pin g, by means of which I can hold the arm f in any one of several given positions with respect to the gear F. Inasmuch as I provide a series of holes h in a circle in the gear F, it will be seen, that I can fix the arm f with respect to the gear F, in any one of several positions, by changing the engagement of the pin g, with any one of the holes h. The pin may be made in the form of a bolt and threaded to engage threads in the wheel F, or to engage threads in the holes h. It will be understood, of course, that arm f is suitably pivoted to the shaft G and held in position by any suitable device, such as a nut or pin. To the outer end of the arm f, I pivotally attach a rod H which extends to the front of the furnace which is assumed to be at the right of the drawing, and from this position, the damper D can be regulated through the medium of the rod H.

It will be seen, therefore, that regardless of the position of the horizontal axis of the radiator extending from left to right through the center G of the furnace, the lever H can be retained always in substantially the same position, with reference to the base of the furnace. This arrangement is important inasmuch as it enables the damper mechanism to be put in position at the factory, and when the furnace is set up, the local conditions will not in any way affect the operation of the damper. The only thing necessary is to adjust the arm f with the pin g in the proper hole h, which will throw the lever H in the right position.

I might add with regard to the arrangement of locating the gear F centrally as explained in the preceding that the arrangement is also advantageous inasmuch as it insures a standard, definite position for the handle of the damper located at the right hand extremity of the rod H. It also enables all of rods H to be cut of standard length and constructed cheaply.

It will be understood, of course, that the ring radiator X rests on top of the stove, which may be of the usual upright type, and that the central vertical axis of the radiator coincides with the central vertical axis of the stove, so that the gases pass from the fire box directly into the forward part of the central cross passage-way dividing thence into the branches A and B.

With reference to the means for interlocking the arm, f, with the gear wheel, F, this means involves the pin, g, already referred to. It will be understood that the pin, g, is

operated like any coupling pin, such action being so well known as it is thought unnecessary to describe the same in further detail.

What I claim is:

1. The combination of a furnace radiator, a damper in said radiator, a controller member for operating said damper, said member being pivoted at a point on the radiator in the vertical central axis thereof and operating in a horizontal plane thereto, an arm for operating said controller, said arm also being pivoted at a point on the radiator in the same vertical axis as said controller member whereby either the said controller member or the said arm may be rotated independently of the other, and whereby any one of several positions between the two may be obtained, and means for locking the said arm and the said controller together. 75

2. The combination of a furnace radiator, a damper in said radiator, a controller member for operating the damper, said member being pivoted at a point on the radiator in the vertical central axis thereof and operating in a horizontal plane thereto, an arm for operating said controller, said arm being pivoted at a point on the radiator located in the same vertical axis as said controller whereby either the said controller or the said arm may be rotated independently of the other, and whereby any one of said relative positions between the two may be obtained, means for locking the said arm and the said controller together, and an operating link pivotally attached to said arm and terminating in a handle, whereby whatever rotary position the radiator may have relative to the rest of the furnace the handle may always find a constant position relative to the rest of the furnace. 100

3. A radiator for a heating furnace, flues in said radiator for connecting the fire box and the chimney, all of said flues meeting at a common point in the rear of the radiator adjacent to the chimney, one of said flues serving to directly connect the combustion chamber with the chimney, the other of said flues arranged to form branching paths from the fire box about the circumference of the radiator to the chimney, a damper located in the direct flue at a point between the combustion chamber and the rear merging point, and a rotatable member horizontally disposed and pivoted with its axis of rotation coincident with the central vertical axis of the furnace, said rotatable member connected with said damper, whereby the said damper may be regulated by rotating said member. 110

4. A radiator for a heating furnace, flues in said radiator for connecting the fire box and the chimney, all of said flues meeting at a common point in the rear of the radiator adjacent to the chimney, one of said flues serving to directly connect the combustion 120

- chamber with the chimney, the other of said flues arranged to form branching paths from the fire box about the circumference of the radiator to the chimney, a damper located in the direct flue at a point between the combustion chamber and the rear merging point, a rotatable member horizontally disposed and pivoted with its axis of rotation coincident with the central vertical axis of the furnace, said rotatable member connected with said damper, whereby the said damper may be regulated by rotating said member, and an adjustable controlling device for said rotatable member comprising an element extending in a direction perpendicular to the front of the furnace, whereby the said perpendicular element may retain the same position, regardless of the position of any one of the horizontal diameters of the radiator.
5. A radiator for a heating furnace, flues in said radiator for connecting the fire box and the chimney, all of said flues meeting at a common point in the rear of the radiator adjacent to the chimney, one of said flues serving to directly connect the combustion chamber with the chimney, the other of said flues arranged to form branching paths from the fire box about the circumference of the radiator to the chimney, a damper located in the direct flue at a point between the combustion chamber and the rear merging point, a rotatable member horizontally disposed and pivoted with its axis of rotation coincident with the central vertical axis of the furnace, said rotatable member connected with said damper, whereby the said damper may be regulated by rotating said member, and an adjustable controlling device for said rotatable member comprising an element extending in a direction perpendicular to the front of the furnace, whereby the said perpendicular element may retain the same position, regardless of the position of any one of the horizontal diameters of the radiator.
10. The combination of a furnace radiator having semi-annular smoke passages and a central cross passageway connecting said semi-annular passageways, a damper within said central passageways, a lever for operating said damper, and means for rotating said lever to any one of a plurality of positions in a horizontal plane with respect to said radiator for adjusting the position of said damper.
15. The combination of a furnace radiator having passageways therein, a damper pivotally secured in one of the passageways in said radiator, a controller member connected to operate said damper and mounted rotatably in the vertical central axis of said radiator to operate in a horizontal plane thereto, and an operating arm adjustably secured to said controller member.
20. The combination of a furnace radiator having passageways therein, a damper pivotally secured in one of the passageways in said radiator, a controller member connected to operate said damper and mounted rotatably in the vertical central axis of said radiator to operate in a horizontal plane thereto, and an operating arm pivoted concentrically with said controller member and adjustably connected thereto.
25. The combination of a furnace radiator having passageways therein, a damper pivotally secured in one of the passageways in said radiator, a controller member connected to operate said damper and mounted rotatably in the vertical central axis of said radiator to operate in a horizontal plane thereto, and an operating arm pivoted concentrically with said controller member and adjustably connected thereto.
30. The combination of a furnace radiator having passageways therein, a damper pivotally secured in one of the passageways in said radiator, a controller member connected to operate said damper and mounted rotatably in the vertical central axis of said radiator to operate in a horizontal plane thereto, and an operating arm pivoted concentrically with said controller member and adjustably connected thereto.
35. The combination of a furnace radiator having passageways therein, a damper pivotally secured in one of the passageways in said radiator, a controller member connected to operate said damper and mounted rotatably in the vertical central axis of said radiator to operate in a horizontal plane thereto, and an operating arm pivoted concentrically with said controller member and adjustably connected thereto.
40. The combination of a furnace radiator having passageways therein, a damper pivotally secured in one of the passageways in said radiator, a controller member connected to operate said damper and mounted rotatably in the vertical central axis of said radiator to operate in a horizontal plane thereto, and an operating arm pivoted concentrically with said controller member and adjustably connected thereto.

In witness whereof, I have hereunto signed my name, this 23rd day of August, 1920.

E. C. TAYLOR.
